(57) CLAIM

The ornamental design for a beach umbrella anchor, as shown and described.

DESCRIPTION

FIG. 1 is a side perspective view thereof;

FIG. 2 is a side perspective view thereof in an assembled position;

FIG. 3 is a top view thereof;

FIG. 4 is a bottom view thereof; and,

FIG. 5 is a side view thereof.

The beach umbrella anchor is shown with symbolic break lines; the appearance of any portion of the article beyond the break lines forms no part of the claimed design.

The pole portions shown in dashed lines on either side of the beach umbrella anchor in FIG. 2 is included for the purpose of illustrating environment and forms no part of the claim.

1 Claim, 1 Drawing Sheet
